SUPERVISORY CONTROL SYSTEM

James H. Oliver, Aldan, Pa., assignor to General
Electric Company, a corporation of New York

Application September 12, 1933, Serial No. 689,087

11 Claims. (Cl. 177—353)

My invention relates to supervisory control systems for supervising and controlling apparatus in a remote station from a control station, such as a dispatcher's office.

5 One object of my invention is to provide an improved two-wire supervisory control system whereby a desired apparatus unit in a remote station may be selected by transmitting to the remote station a predetermined code of impulses 10 over the two-line conductors. The selection may be checked by transmitting over the two conductors to the control station a predetermined check code corresponding to the selected unit, and the 15 operation of the selected unit can be effected by an impulse transmitted over the two conductors only if the selected unit is the proper one.

Another object of my invention is to provide 20 an arrangement whereby in addition to a check code being transmitted to the control station after an apparatus unit has been selected, an indication of the position of the selected unit is also transmitted over the two-line conductors before the selected unit can be operated.

Another object of my invention is to provide 25 an improved two-wire supervisory control system of the above type which requires a minimum amount of apparatus and a minimum amount of time to effect a desired supervisory and control operation.

30 My invention will be better understood from the following description when taken in connection with the accompanying drawings and its scope will be pointed out in the appended claims.

Referring to the drawings which comprise 35 Figs. 1 to 4 inclusive, sufficient apparatus and circuits of a supervisory control system embodying my invention have been shown by means of the usual conventional diagrams to enable my invention to be readily explained and understood.

40 The apparatus and circuits shown in Figs. 1 and 2 are those located in the control or dispatcher's office while the apparatus and circuits shown in Figs. 3 and 4 are those located at the remote station which is connected to the dispatcher's office by only two line conductors L—1 and L—2.

45 In practicing my invention I provide at the dispatcher's office a group of control keys and indicating lamps for each apparatus unit to be selected and controlled in the remote station. 50 In order to simplify the disclosure, only two groups of keys and lamps are shown. Each group of keys consists of a two-position select key, such as SK—3 and SK—23, which is operated by the dispatcher when he desires to select a corresponding apparatus unit for operation, and a

two-position control key such as CK—3 and CK—23 which controls the operation of the corresponding indicating lamps. Each group of indicating lamps consists of a red lamp such as R—3 and R—23 which when lighted indicates 5 that the corresponding apparatus unit is in its closed position, a green lamp such as G—3 and G—23 which when lighted indicates that the corresponding apparatus unit is in its open position, a white lamp such as W—3 and W—23 10 which when lighted indicates that the position of the corresponding apparatus unit does not correspond with the position of the associate control key and an amber lamp such as AM—3 and AM—23 which when lighted indicates that 15 the corresponding apparatus unit has been properly selected for operation. Each group of keys and lamps has associated therewith an individual indicating relay, such as IR—3 and IR—23, 20 which determines by its position whether the associated red or green lamp is lighted and which cooperates with the associated control key to determine whether the associated white lamp is lighted. The position of each indicating relay in 25 turn is determined by the position of the corresponding apparatus unit in a manner which will be hereinafter described. As shown in Fig. 1, the indicating relays IR—3 and IR—23 are in the position they occupy when the corresponding apparatus units are in their open positions and the control keys CK—3 and CK—23 are also 30 shown in the corresponding positions so that the green lamps G—3 and G—23 are lighted and the other lamps are not lighted. It will be seen that if either control key should be moved to its other 35 position, the associate white lamp would be lighted.

In order that the operation of any one of the select keys may effect the selection of the corresponding apparatus unit, a suitable finder and 40 code selector switch 1S and a code sender 2S are provided at the dispatcher's office for transmitting to the remote station over the line conductors L—1 and L—2 a series of seven current impulses, the respective polarities of which vary with the 45 unit to be selected. The finder and code selector switch 1S and the code sender 2S preferably are selector switches of the well-known type which comprise banks of twenty-five contacts, each bank having associated therewith a cooperating 50 wiper. A suitable operating magnet is provided for simultaneously moving all of the wipers in a step-by-step movement over the contacts of the respective banks. Any other suitable switching means, examples of which are well known in 55

the art may be used however. As shown in Fig. 1, the switch $1S$ consists of six blanks $1S-1$ and $1S-6$ inclusive, a cooperating wiper for each bank and an operating magnet $M-1$; and the code sender $2S$ consists of six banks $2S-1$ to $2S-6$ inclusive, a cooperating wiper for each bank and an operating magnet $M-2$.

Normally the switches $1S$ and $2S$ are in their zero or normal positions, as shown in the drawings. Each of the other twenty-four positions of switch $1S$, except the twenty-fourth position, may be allotted to a different apparatus unit so that with the arrangement shown twenty-three different apparatus units can be supervised and controlled. As shown, position 3 of the switch $1S$ is allotted to the apparatus unit corresponding to select key $SK-3$ and position 23 is allotted to the apparatus unit corresponding to select key $SK-23$. When select key $SK-3$ is operated, the motor magnet $M-1$ is arranged to be operated to effect the movement of the switch $1S$ from its normal position to its third position where it will stop and remain as long as the switch $SK-3$ is maintained in its operated position. In similar manner, when the select key $SK-23$ is operated the operating magnet $M-1$ operates to move the switch $1S$ to its twenty-third position where it remains until the select key $SK-23$ is restored to its normal position.

When the switch $1S$ stops in any one of its positions, it sets up a code individual to that position. For example, when it stops in position 3 it sets up a code individual to the select key $SK-3$ and similarly when it stops in position 23, it sets up a code individual to the select key $SK-23$.

At the dispatcher's office a suitable start key ST is provided which the dispatcher operates after he has operated the select key of the desired apparatus unit which he desires to operate. The operation of this start key ST effects the operation of the operating magnet $M-2$ of the code selector $2S$ so that this code selector moves from its normal position to its 18th position. During this operation of the code selector $2S$ a circuit is completed for a code transmitting relay CTR , which is a three-position polarized relay, through the wiper and contacts of the bank $2S-1$ when the switch $2S$ is in positions 3, 5, 7, 9, 11, 13, and 15. The direction of the current flow through these circuits of the code-transmitting relay CTR depends upon the position of the code selector switch $1S$. When a positive potential is connected to a contact of bank $2S-1$, the code-transmitting relay CTR operates in a direction to cause a positive impulse to be transmitted over the line conductors $L-1$ and $L-2$ and when a negative potential is connected to a contact of bank $2S-1$ the code-transmitting relay CTR operates to cause a negative impulse to be transmitted over the line conductors. In this manner a series of seven positive and negative impulses is transmitted to the remote station to select the desired apparatus unit.

At the remote station this series of seven positive and negative impulses energizes a code-responsive relay CRR' which is a three-position polarized relay. Each energization of the code-responsive relay CRR' effects the operation of a selector switch $1S'$, comprising six banks of twenty-five contacts $1S'-1$ to $1S'-6$ inclusive and an operating magnet $M'-1$, and the energization of one of the selective relays $20'-33'$ inclusive so that in response to the code of im-

pulses transmitted thereto the relays $20'-33'$ inclusive are selectively operated to effect the selection of the desired apparatus unit.

After the selecting code of impulses has been transmitted and correctly received by the receiving apparatus in the remote station, the operation of another selector switch $2S'$, comprising six banks of twenty-five contacts $2S'-1$ to $2S'-6$ inclusive and an operating magnet $M'-2$, is effected. This selector switch $2S'$ has a separate position allotted to each apparatus unit. As shown, positions 3 and 23 of this switch are allotted to the apparatus units $AU'-3$ and $AU'-23$ respectively. These apparatus units are shown as circuit breakers of the well-known latched-in type, but it is obvious that each apparatus unit may be any other suitable control device. Each circuit breaker is provided with a suitable closing coil, such as closing coil $CC'-3$ for apparatus unit $AU'-3$ and closing coil $CC'-23$ for apparatus unit $AU'-23$ and with a suitable trip coil such as trip coil $TC'-3$ for apparatus unit $AU'-3$ and $TC'-23$ for apparatus unit $AU'-23$. Associated with each apparatus unit is a control relay, such as $CR'-3$ and $CR'-23$ for apparatus units $AU'-3$ and $AU'-23$ respectively, which selectively controls the energization of the closing and tripping coils of the corresponding apparatus unit. As shown, these control relays are three-position polarized relays of the well-known type whose armature returns to its neutral position when the relay is deenergized. The circuits of the control relay windings are respectively connected to the contacts of bank $2S'-5$ allotted to the corresponding apparatus units. For example, the circuit of the control relay $CR'-3$ can be completed only through the third off-normal contact in bank $2S'-5$ and the circuit of control relay $CR'-23$ can be completed only through the twenty-third off-normal contact of bank $2S'-5$.

In order to stop the selector switch $2S'$ in the position corresponding to the apparatus unit selected, the relays $20'-33'$ are arranged to connect a potential to the contact in bank $2S'-2$ which is allotted to the selected unit. When the switch $2S'$ reaches that position, the relay $1'$ is energized to open the circuit of the operating magnet $M'-2$ so as to cause the switch $2S'$ to remain in that position.

At the remote station there is also a finder and a code selector switch $3S'$ which is similar in construction and operation to the finder and code selector $1S$ in the dispatcher's office. The switch $3S'$ is controlled by the operation of the switch $2S'$ so that they always occupy corresponding positions. Therefore, when the switch $2S'$ is moved to the position allotted to a selected apparatus unit, the switch $3S'$ is moved to the corresponding position and sets up the code of impulses of the selected apparatus unit.

As soon as both of the switches $2S'$ and $3S'$ have reached the positions allotted to the selected apparatus unit, a code sender $4S'$ is operated in the remote station to transmit over the line conductors $L-1$ and $L-2$ the code of impulses set up by the switch $3S'$. This code selector $4S'$ comprises six banks of twenty-five contacts $4S'-1$ to $4S'-6$ inclusive and an operating magnet $M'-4$. During the operation of this code sender from its normal position to its twenty-second position, a circuit is first completed for a transfer relay $35'$ to transfer the line conductors $L-1$ and $L-2$ at the remote

station from the code-receiving relay CRR' to the core-transmitting relay CTR' which is a three-position polarized relay. After this change in connections has been established, a series of seven positive and negative impulses is transmitted to the winding of the code-transmitting relay CTR' which causes a corresponding series of impulses to be transmitted over the line conductors L-1 and L-2 to the dispatcher's office. Then finally a polarity impulse corresponding to the position of the selected apparatus unit is transmitted to the code-transmitting relay CTR' which in turn transmits a corresponding impulse over the line conductors. At the dispatcher's office these impulses operate a code-responsive relay CRR, which is a three-position polarized relay. Each operation of the code-responsive relay CRR effects the operation of a selector switch 3S comprising four banks of twenty-five contacts 3S-1 to 3S-4 inclusive and an operating magnet M-3 and the selective operation of a group of selector relays 10-26 inclusive. After this series of impulses has been transmitted, circuits are completed by the operated control relays in the dispatcher's office for the amber lamp and the indicating relay associated with the operated select key and for a common check relay 14^a. The lighting of the amber lamp informs the dispatcher that the selection has been properly made and the operation of the indicating relay checks the indicating lamps and effects any change that is necessary in order to make them correspond with the position of the corresponding apparatus unit. The energization of the check relay 14^a prepares a circuit whereby the dispatcher may now operate the selected apparatus unit.

For operating a selected apparatus unit a two-position operate key OK is provided at the dispatcher's office. After receiving the indication that the proper apparatus unit has been selected, the dispatcher first moves the control key of the selected apparatus unit to the position corresponding to the one to which he wants to operate the apparatus unit and then he operates the operate key OK. A circuit is then completed for a predetermined time interval for a control relay 16^a which when energized disconnects the code-receiving relay CRR from the line conductors L-1 and L-2 and connects the line conductors to the battery BAT so that a negative impulse is transmitted over the line conductors. As long as this operate impulse is being transmitted, an operate lamp OL is lighted in the dispatcher's office.

At the remote station this negative impulse effects the operation of the code-receiving relay CRR' which in turn effects the connection of the proper polarity to the winding of the polarized control relay of the selected apparatus unit so that it in turn effects the desired operation of the selected apparatus unit. When the operate impulse is cut off from the line conductors L-1 and L-2, the code-responsive relay CRR in the dispatcher's office is reconnected across the line conductors and in the remote station the transfer relay 35' is energized for a predetermined time to disconnect the code-receiving relay CRR' from the line conductors and to connect the line conductors to the contacts of the code-transmitting relay CTR'. The code transmitting relay CTR' is then energized in accordance with the new position of the selected apparatus unit and causes an indicating impulse corresponding to this new position to be transmitted to the dispatcher's

office. After this indicating impulse has been transmitted for a predetermined time, the receiving equipment at the remote station is again connected across the line conductors so that it is ready to receive the next control impulse.

At the dispatcher's office the indicating impulse operates the code-receiving relay CRR in the proper direction to cause the indicating relay corresponding to the selected apparatus unit to move to the position corresponding to the new position of the selected apparatus unit. The indicating relay in turn controls the circuits of the lamps corresponding to the selected apparatus unit so that they indicate the new position there-

of. The dispatcher may operate the selected apparatus unit as many times as desired by successively operating the operate key before the selection is released. After each operation, the corresponding signalling lamps are operated to indicate the new position of the operated unit.

After the last operation has been performed, the dispatcher can release the selection and restore the apparatus to normal merely by restoring the operated select key to its normal position. As soon as the apparatus reaches its zero position, an alarm ALM is operated and a start lamp STL is lighted to indicate that the system is ready for a new operation.

In order that any change in the position of an apparatus unit, not effected by the dispatcher, may also be indicated in the dispatcher's office, each apparatus unit has associated therewith an indicating relay, such as relay IA'-3 and IA'-23 for apparatus unit AU'-3 and AU'-23 respectively, which operates in response to each change in the position of the associate apparatus unit to cause the switch 2S' to move to the position thereof allotted to the apparatus unit which has changed its position. Switches 3S' and 4S' then operate to effect the transmission of the code of impulses corresponding to the operated apparatus unit and an impulse corresponding to the new position thereof. At the dispatcher's office these impulses effect the operation of the selector switch 3S and of the relays 10-26 inclusive so that an alarm ALM is operated to inform the dispatcher that an apparatus unit has changed its position and the indicating relay corresponding to the operated apparatus unit is operated to the position corresponding to the new position of the apparatus unit. The indicating lamps corresponding to the operated apparatus unit are thereby lighted in accordance with the new position thereof and the associate white lamp is lighted to indicate to the dispatcher which unit has changed its position. The dispatcher can extinguish the white lamp by moving the associate control key to the position corresponding to the new position of the unit.

The alarm ALM is controlled by a two-position key AK. With this key AK in one position, the alarm operates continuously when an apparatus unit changes its position. When the alarm key AK is in its other position, the alarm is operated for only a short time. The continuous operation of the alarm may be stopped by the operator moving the alarm key to its other position.

The detailed operation of the system shown is as follows: With the system at rest and in an operative condition, a circuit is completed for the start lamp STL through the contacts 100 of the zero position check relay 1 which is energized. At the remote station when both of the switches 1S' and 4S' are in their normal positions, a cir-

cuit is completed from the positive terminal of a battery BAT', through the wiper and normal contact of bank 1S-4, conductor 400, winding of relay 1', wiper and normal contact of bank 4S-4, to the negative terminal of battery BAT'. By closing its contacts 300 and 306, the relay 1' completes a check circuit through the line conductors L-1 and L-2 from the positive terminal of the battery BAT', through contacts 300 of relay 1', conductor 301, contacts 302 of relay 12', conductor 303, winding of code-receiving relay CRR', conductor 401, contacts 304 of transfer relay 35', line conductor L-1, contacts 101 of relay 16a, conductor 102, contacts 103 of relay 28, 15 winding of code-receiving relay CRR, wiper and normal contact of bank 2S-3, line conductor L-2, contacts 305 of transfer relay 35', contacts 306 of relay 1' to the negative terminal of the battery BAT'. The direction of current flow in 20 this circuit is such that the contacts 402 of relay CRR' and contacts 104 of relay CRR are closed. The closing of the contacts 402 completes a circuit from the positive terminal of battery BAT', through winding of relay 3', contacts 402 of relay 25 CRR', wiper and normal contact of bank 1S-2, conductor 465, winding of relay 36' to the negative terminal of battery BAT'. By closing its contacts 403, the relay 3' completes an obvious circuit for the relay 4'. 30

In the dispatcher's office, the relay CRR completes a circuit from the positive terminal of the battery BAT, through the winding of relay 1, conductor 200, contacts 104 of relay CRR, conductor 105, wiper and normal contact of bank 3S-1, conductor 201, winding of check relay 1, conductor 106, wiper and normal contact of bank 2S-4 to the negative terminal of the battery BAT. Contacts 202 of relay 1 complete an obvious circuit for relay 8 which is of the slow-to-drop-out 35 type. Contacts 100 of relay 1 complete the contacts of the start lamp STL and the contacts 107 complete a holding circuit for the alarm relay 2 through the contacts 108 of the alarm relay. Since either a short circuit or open circuit on the 40 line wires would deenergize the relay CRR in the dispatcher's office, and this relay in turn would deenergize the check relay 1, it is evident that when the start lamp STL is lighted it indicates 45 that all of the equipment is in the zero or starting position and that the line wires L-1 and L-2 are in an operative condition.

In order to describe the operation of the arrangement shown, it will be assumed that the apparatus unit AU'-23 is open and that the dispatcher desires to close this apparatus unit. After first observing that the start lamp STL is lighted, the dispatcher operates the select key SK-23 corresponding to the desired apparatus unit. The operation of this select key results in 55 the opening of the contacts 109, and the closing of contacts 110 and 111. By opening contacts 109 and closing contacts 110, a high resistance relay 5 is inserted between the 23rd contact of bank 1S-6 and the positive terminal of battery BAT. 60 The closing of contacts 111 completes through the wiper and normal contact of 1S-6 and interrupter contacts IC-1 an energizing circuit for the operating magnet M-1. Magnet M-1 then operates in a manner well known in the art to move 65 the selector switch 1S from its zero position to position 1 and then continues to move the switch to its 23rd position since each contact of bank 1S-6 is normally connected to the positive terminal of battery BAT. When the 23rd position is reached, sufficient current does not flow 70

through the relay 5 and the operating magnet M-1 to effect the operation of the operating magnet. However, relay 5 operates and by closing its contacts 112 connects the seventh off-normal contact of bank 2S-1 to the negative terminal 5 of battery BAT. This relay 5 is common to a number of select keys, not shown, and is arranged so that when any one of these particular select keys is operated, the seventh off-normal contact of bank 2S-1 is disconnected from the positive 10 terminal of battery BAT and is connected to the negative terminal thereof.

In positions 1-23 of switch 1S a circuit is completed through the wiper of bank 1S-5, winding of relay 4 which is of the slow pick-up type, contacts 113 of emergency reset key ERK, wiper and normal contact of bank 2S-2 to the neutral terminal of battery BAT. Since adjacent contacts of bank 1S-5 are connected to opposite terminals of battery BAT, the reversals of current 20 which occur through the winding of relay 4 prevent the relay from picking up during the notching operation of the switch. After the switch 1S stops in its 23rd position however the relay 4 picks up and completes through its contacts 114 25 a locking circuit for itself which is independent of the wiper of bank 2S-2 so that the subsequent movement of switch 2S does not result in the de-energization of relay 4. By opening its contacts 115, the relay 4 disconnects the 18th off-normal 30 contact of bank 2S-6 from the negative terminal of battery BAT.

The code corresponding to apparatus unit AU'-23 is now set up by the polarities impressed on the off-normal contacts 3, 5, 7, 9, 35 11, 13, and 15 of bank 2S-1. With the particular arrangement shown in the drawings, the polarity of the first two impulses is fixed and so the off-normal contacts 3 and 5 of bank 2S-1 are permanently connected to the positive terminal 40 of battery BAT. Since relay 5 is energized, when select key SK-23 is operated, the 7th off-normal contact of bank 2S-1 is connected to the negative terminal of battery BAT. The polarities connected to off-normal contacts 9, 11, 13, 45 and 17 are determined by the positions of the wipers of banks 1S-2, 1S-3, 1S-4, 1S-5, respectively. In the 23rd position of switch 1S, the wipers 1S-2 and 1S-5 are connected to the positive terminal of battery BAT and the wipers 50 1S-3 and 1S-4 are connected to the negative terminals of battery BAT. Therefore, the code for apparatus unit AU'-23 is positive, positive, negative, positive, negative, negative, positive.

After the dispatcher operates the select key 55 SK-23, he operates the start key ST so that contacts 116 are closed and contacts 117 are open. A circuit is then completed from the negative terminal of battery BAT, through contacts 116, conductor 118, contacts 119 of relay 4, contacts 120 of check relay 1, conductor 121, wiper and normal contact of bank 2S-6, interrupter contact IC-2, winding of relay 6 to neutral terminal of battery BAT. After a time delay relay 6 closes its contacts 121a and completes an energizing circuit for the operating magnet M-2 of selector switch 2S. Magnet M-2 by opening its interrupter contacts IC-2 interrupts the above-traced circuit for relay 6 so that relay 6 drops out and opens the energizing circuit of the operating magnet M-2 which causes the switch 2S to move from its normal position to position 1. Since the off-normal contacts 1-17 inclusive of bank 2S-6 are connected to the negative terminal of battery BAT, relay 6 and operating mag- 75

net M—2 are alternately energized and deenergized to effect the movement of switch 2S from position 1 to position 18 in which position the circuit of relay 6 is open at the contacts 115 of relay 4. As selector switch 2S moves from position 1 to position 18, the wiper of bank 2S—1 engages the contacts to which the code impulse potentials are applied and completes through contacts 122 of relay 28 an energizing circuit for the operating winding of the code-transmitting relay CTR, which is a three-position polarized relay.

When the wiper of bank 2S engages a contact which is connected to the positive terminal of battery BAT, the code-transmitting relay CTR is operated to close its contacts 123 and 124 so that the line conductors L—1 and L—2 are connected to the positive and negative terminals of battery BAT respectively, and when the wiper of bank 2S—1 engages a contact which is connected to the negative terminal of battery BAT the relay CTR closes its contacts 125 and 126 so that the line conductors L—1 and L—2 are connected to the negative and positive terminals of battery BAT respectively.

When the selector switch 2S leaves its zero position, the heretofore traced zero position check circuit is interrupted by the wiper of bank 2S—3 leaving its normal contact. Therefore, the relays CRR and CRR' becomes deenergized and their armatures are restored to their neutral positions. In the dispatcher's office, the opening of the contacts 104 of relay CRR effects the deenergization of the relays 1, 7, and 8. The deenergization of the relays 7 and 8 has no effect at this time. By opening its contacts 100 the check relay 1 extinguishes the start lamp STL and by opening its contacts 107 it interrupts the circuit of the alarm relay 2. Although the alarm relay 40 closes its contacts 127, the alarm is not operated at this time because the circuit thereof is open at the contacts 117 of the start key ST.

In the remote station, the opening of the contacts 492 of relay CRR' interrupts the heretofore described circuit of relays 3' and 36'. Relay 3' by opening its contacts 403 and closing its contacts 404 completes an energizing circuit for the operating magnet M'—1 of switch 1S' to effect the movement of this switch from its zero position to position 1. This circuit is from the negative terminal of battery BAT' through contacts 404 of relay 3', contacts 405 of relay 4', wiper and normal contact of bank 1S'—6, winding of magnet M'—1, interrupter contact IC'—1 to the neutral terminal of battery BAT'. Although the circuit of relay 4' is interrupted by the opening of contacts 403, this relay 4', which is of the slow drop-out type, is so adjusted that it maintains the above-traced circuit for the operating magnet M'—1 completed for a sufficient length of time to effect the movement of the selector switch 1S' to its first position.

Therefore, it will be seen that by the time the selector switch 2S in the dispatcher's office reaches its third position, the selector switch 1S' in the remote station is in its first position. Each time the code-transmitting relay CTR is operated to transmit an impulse, a circuit is completed for the code-receiving relay CRR' which is connected across the line conductors L—1 and L—2 through contacts 304 of the transfer relays 35', conductor 401, winding of relay CRR', conductor 303, contacts 302 of relay 12', conductor 301, contacts 307 of relay 1' which is deenergized as soon as switch 1S' leaves its normal position, conductor 308,

wiper and normal contact of bank 4S'—1, conductor 309, contacts 310 of relay 1' and contacts 305 of relay 35'. When the contacts 123 and 124 of the code-transmitting relay CTR are closed, the positive impulse which is transmitted over the line conductors L—1 and L—2 causes the code-receiving relay CRR' to close its contacts 406 and when the contacts 125 and 126 of the code-transmitting relay CTR are closed, the negative impulse which is transmitted over the line conductors L—1 and L—2 causes the code-receiving relay CRR' to close its contacts 402. Therefore, when the switch 2S reaches its third position and the code-transmitting relay CTR is operated to transmit a positive impulse, the code-receiving relay CRR' completes a circuit from the positive terminal of battery BAT' through winding of relay 3', contacts 406, wiper and first contact of bank 1S'—1, conductor 407, winding of relay 22', conductor 408, contacts 409 of relay 36' to the negative terminal of battery BAT'. Relay 22' by closing its contacts 410 completes a locking circuit for itself to the neutral terminal of battery BAT'. As soon as the switch 2S leaves its third position and the positive impulse is disconnected from the line conductors, relay 3' closes its contacts 404 and completes a circuit from the negative terminal of battery BAT', through contacts 404 of relay 3', conductor 412, contacts 411 of relay 22', conductor 413, wiper and first contact of bank 1S'—6, winding of magnet M'—1, interrupter contact IC'—1 to the neutral terminal of battery BAT'. Magnet M'—1 then operates to move the switch 1S' to its second position.

When the switch 2S reaches its fifth position, the code-transmitting relay CTR again operates to transmit a positive impulse over the line conductors so that the code-receiving relay CRR' again closes its contacts 406. A circuit is now completed from the positive terminal of battery BAT' through relay 3', contacts 406, wiper and second off-normal contact of bank 1S'—1, conductor 414, winding of relay 23', conductor 408, contacts 409 of relay 36' to the negative terminal of battery BAT'. By closing its contacts 415, the relay 23' completes a locking circuit to the neutral terminal of battery BAT'. When the switch 2S leaves its fifth position, the second impulse is cut off and the code-receiving relay CRR' operates to interrupt the circuit of relay 3'. By closing its contacts 404, the relay 3' completes a circuit from the negative terminal of battery BAT' through contacts 404, conductor 412, contacts 416 of relay 23', conductor 417, wiper and second off-normal contact of bank 1S'—6, magnet M'—1, interrupter contact IC'—1 to the neutral terminal of battery BAT'. Magnet M'—1 then effects the movement of switch 1S' to its third position.

When the switch 2S reaches its seventh position, the third impulse which is a negative impulse is transmitted to the code-receiving relay CRR' so that this relay closes its contacts 402. A circuit is then completed from the positive terminal of battery BAT', through winding of relay 3', contacts 402 of relay CRR', wiper and third off-normal contact of bank 1S'—2, conductor 418, winding of relay 25', conductor 419, contacts 420 of relay 36' to the negative terminal of battery BAT'. By closing its contacts 421, the relay 25' completes a locking circuit for itself to the neutral terminal of battery BAT'. As soon as the switch 2S leaves its seventh position, the negative impulse is cut off and relay CRR' opens its contacts 402.

- contacts 402 so that the relay 3' is deenergized. A circuit is then completed from the negative terminal of battery BAT', through contacts 404 of relay 3', conductor 412, contacts 422 of relay 25', conductor 423, wiper and third off-normal contact of bank 1S'-6, winding of magnet M'-1, interrupter contact IC'-1 to the neutral terminal of battery BAT'. Magnet M'-1 then operates to move the switch 1S to its fourth position.
- 10 When the switch 2S reaches its ninth position, the code-transmitting relay CTR is operated to transmit the fourth impulse which is a positive impulse to the code-receiving relay CRR' so that it closes its contacts 406. A circuit is then completed from the positive terminal of battery BAT', through winding of relay 3', contacts 406 of relay CRR', wiper and fourth off-normal contact of bank 1S'-1, conductor 424, winding of relay 26', conductor 408, contacts 409 of relay 36' to the negative terminal of battery BAT'. By closing its contacts 425 relay 28' completes a locking circuit for itself to the negative terminal of battery BAT'. As soon as switch 2S leaves its ninth position, the fourth impulse is cut off and relay CRR' opens its contacts 406 to interrupt the circuit of relay 3'. A circuit is then completed from the negative terminal of battery BAT' through contacts 404 of relay 3', conductor 412, contacts 426 of relay 26', conductor 427, wiper and fourth off-normal contact of bank 1S'-6, winding of magnet M'-1, interrupter contact IC'-1 to the neutral terminal of battery BAT'. Magnet M'-1 then operates to effect the movement of switch 1S' to its fifth position.
- 15 When the switch 2S reaches its eleventh position the code-transmitting relay CTR transmits the fifth impulse which is a negative impulse to the code-receiving relay CRR' so that this relay closes its contacts 402. A circuit is then completed from the positive terminal of battery BAT' through winding of relay 3', contacts 402 of relay CRR', wiper and fifth off-normal contact of bank 1S'-2, conductor 428, winding of magnet 29', conductor 419, contacts 420 of magnet 36' to the negative terminal of battery BAT'. By closing its contacts 429, relay 29' completes a locking circuit for itself to the neutral terminal of battery BAT'. When the switch 2S leaves its eleventh position, the fifth impulse is cut off and relay CRR' opens its contacts 402 so that the relay 3' is deenergized. A circuit is then completed from the negative terminal of battery BAT' through contacts 404 of relay 3', conductor 412, contacts 430 of relay 29', conductor 431, wiper and fifth off-normal contact of bank 1S'-6, winding of magnet M'-1, interrupter contact IC'-1 to the neutral terminal of battery BAT'. Magnet M'-1 then operates to effect the movement of switch 1S' to its sixth position.
- 20 When the switch 2S reaches its thirteenth position the code-transmitting relay CTR is operated to transmit the sixth impulse, which is a negative impulse, to the code-receiving relay CRR' so that it closes its contacts 402. A circuit is then completed from the positive terminal of battery BAT' through the winding of relay 3', contacts 402 of relay CRR', wiper and sixth off-normal contact of bank 1S'-2, conductor 432, winding of relay 31', conductor 419, contacts 420 of relay 36' to the negative terminal of battery BAT'. By closing its contacts 433, relay 31' completes a locking circuit for itself to the neutral terminal of battery BAT'. When switch 2S leaves its thirteenth position, the sixth impulse is cut off and relay CRR' opens its contacts

402 and interrupts the circuit of relay 3'. A circuit is then completed from the negative terminal of battery BAT', through contacts 404 of relay 3', conductor 412, contacts 434 of relay 31', conductor 435, wiper and sixth off-normal contact of bank 1S'-6, winding of magnet M'-1, interrupter contact IC'-1 to the neutral terminal of battery BAT'. Magnet M'-1 then operates to effect the movement of switch 1S' to its seventh position.

When switch 2S reaches its fifteenth position, the code-transmitting relay CTR is operated to transmit the seventh impulse which is a positive impulse to the code-receiving relay CRR' so that it closes its contacts 406. A circuit is then completed from the positive terminal of battery BAT' through winding of relay 3', contacts 406 of relay CRR', wiper and seventh off-normal contact of bank 1S'-1, conductor 436, winding of magnet 32', conductor 408, contacts 409 of relay 36' to the negative terminal of battery BAT'. By closing its contacts 437, relay 32' completes a locking circuit for itself through the neutral terminal of battery BAT'. By closing its contacts 451, relay 32' completes an obvious circuit for the control relay 20'. When switch 2S leaves its fifteenth position, the seventh impulse is cut off and relay CRR' opens its contacts 406 to deenergize relay 3'. A circuit is then completed from the negative terminal of battery BAT' through contacts 404, conductor 412, contacts 438 of relay 32', conductor 439, wiper and seventh off-normal contact of bank 1S'-6, winding of magnet M'-1, interrupter contact IC'-1 to the neutral terminal of battery BAT'. Magnet M'-1 then operates to effect the movement of switch 1S' to its eighth position.

Should the remote station fail to receive one or more of the code impulses, the switch 1S' will be in a position between its normal position and position 8 after the last impulse is transmitted. While the code impulses are being transmitted, the interval between successive impulses is not sufficiently long to allow the relay 4' to open its contacts 405 and close its contacts 452. After the last impulse, however, the interval is long enough to allow relay 4' to open its contacts 405 and close its contacts 452. Therefore, if the switch 1S' is in any position between its normal position and position 8, a circuit is completed for the slow-to-drop-out relay 5' from the negative terminal of battery BAT' through contacts 404 of relay 3', contacts 452 of relay 4', wiper and contact of bank 1S'-5, winding of relay 5' to the neutral terminal of battery BAT'. By closing its contacts 453, relay 5' completes a notching circuit for the magnet M'-1 through contacts 452 of relay 4' and contacts 404 of relay 3' to move the switch 1S' from whichever position it is in to position 9. Since the relay 5' is of the slow-to-drop-out type, this notching circuit is maintained by the relay 5' to effect the movement of the switch 1S' through its position 8 although the circuit of relay 5' is open in this position. In positions 9 to 23 inclusive of switch 1S', a notching circuit is completed through the wiper and contacts of switch 1S'-5 and contacts 404 and 452 to restore the switch 1S' to its normal position. Therefore, it will be seen that if one or more impulses of the code are not received or if an extra impulse is transmitted, the switch 1S' is immediately restored to its normal position after the code has been transmitted.

If the impulses are transmitted correctly, the switch 1S' is in its eighth position when the re-

lay 4' closes its contacts 452 after the transmission of the last impulse of the code. A circuit is then completed from the positive terminal of battery BAT' through wiper and eighth off-normal contact of bank 1S'-4, winding of relay 6', wiper and eighth off-normal contact of bank 1S'-5, contact 452 of relay 4', contact 404 of relay 3' to the negative terminal of battery BAT'. By closing its contacts 454, relay 6' completes a locking circuit for itself to the negative terminal of battery BAT'. By closing its contacts 440, relay 6' completes a circuit from the positive terminal of battery BAT' through contacts 440, conductor 441, contacts 311 of relay 19', contacts 312 of relay 7', winding of magnet M'-2, interrupter contact IC'-2 to the neutral terminal of battery BAT'. A notching circuit is thereby completed for the magnet M'-2 so that the switch 2S' is operated until it reaches its twenty-third position which is the position allotted to the apparatus unit AU'-23. A circuit is then completed from the positive terminal of battery BAT' through contacts 442 of relay 6', conductor 443, winding of relay 34', conductor 313, contacts 444 of relay 22', contacts 445 of relay 23', contacts 446 of relay 25', contacts 447 of relay 26', contacts 448 of relay 29', contacts 449 of relay 31', contacts 450 of relay 20', conductor 454, wiper and twenty-third off-normal contact of bank 2S'-2, winding of relay 7' to the negative terminal of battery BAT'. Relays 7' and 34' are energized by the completion of this circuit. By opening its contacts 312, relay 7' interrupts the notching circuit of magnet M'-2 so that the switch 2S' stops in its twenty-third position.

Since corresponding contacts of banks 3S'-6 and 2S'-1 are interconnected, the relay 8' is de-energized to complete through its contacts 314 and the interrupter contacts IC'-3 a notching circuit for the operating magnet M'-3 of switch 3S'. Therefore, since the switch 2S' is operated to the position allotted to the selected apparatus unit, the switch 3S' is also operated to the corresponding position. When both of these switches 2S' and 3S' have stopped in their twenty-third positions which are the positions allotted to the apparatus AU'-23, the relay 8' is energized through the wipers and twenty-third off-normal contacts of the banks 2S'-1 and 3S'-6.

With the switch 3S' stopped in its twenty-third position, the code of the selected apparatus unit which is positive, positive, negative, positive, negative, negative, positive is now set up on the contacts of banks 4S'-3 of code sender switch 4S'. Since the first two impulses are always positive, the seventh and ninth off-normal contacts of bank 4S'-3 are permanently connected to the positive terminal of battery BAT'. The eleventh, fifteenth, and seventeenth off-normal contacts of bank 4S'-3 are respectively connected by the wipers and twenty-third off-normal contacts of banks 3S'-1, 3S'-3, and 3S'-4 to the negative terminal of battery BAT' and the thirteenth and nineteenth off-normal contacts of bank 4S'-3 are respectively connected by the wipers and twenty-third off-normal contacts of banks 3S'-2 and 3S'-5 to the positive terminal of the battery BAT'.

In order that the code-receiving selector 3S in the dispatcher's office may be rendered operative to receive the check code, the fifth off-normal contact of bank 4S'-3 is connected to the negative terminal of battery BAT'. Therefore, a

starting impulse is transmitted to effect the movement of the code selector 3S in the dispatcher's office from its normal position before the check code is transmitted thereto.

The position of the selected unit is indicated by the potential applied to the twenty-first and twenty-second off-normal contacts of bank 4S'-3 by the wiper of bank 2S'-6. Since switch 2S' is in its twenty-third position and the apparatus AU'-23 is open and its auxiliary contacts 321 are closed, the positive terminal of battery BAT' is connected to both the twenty-first and the twenty-second off-normal contacts of bank 4S'-3. If the apparatus unit AU'-23 were closed, its auxiliary contacts 321 would be open 15 and its auxiliary contacts 322 would be closed so that the negative terminal of battery BAT' would be connected to the twenty-first and twenty-third off-normal contacts of bank 4S'-3.

In position 23, the wiper of bank 2S'-6 also 20 connects the winding of a control selection relay CSR' between the neutral terminal and either the positive or negative terminal of battery BAT', depending upon the position of the apparatus unit AU'-23. Relay CSR' which is a two-position 25 polarized relay, is arranged to close its contacts 333 and 334 when the winding thereof is connected to the positive terminal of battery BAT' and to close its contacts 335 and 336 when the winding thereof is connected to the negative 30 terminal. With the apparatus unit AU'-23 in the position shown, the relay CSR' operates to close its contacts 333 and 334 when the switch 2S' stops in its position 23.

When both of the switches 2S' and 3S' have 35 stopped in their twenty-third position and relay 8' is energized, a circuit is completed from the negative terminal of battery BAT' through contacts 315 of relay 8', contacts 316 of relay 7', conductor 317, contacts 318 of relay 9', conductor 319, wiper and normal contact of bank 4S'-6, interrupter contact IC'-4, winding of relay 10' to the neutral terminal of battery BAT'. By closing its contacts 320, relay 10' which is of the slow pick-up type completes through the 40 wiper and normal contact of bank 4S'-5 a circuit for the operating magnet M'-4 of switch 4S'. By opening the interrupter contacts IC'-4, the magnet M'-4 interrupts the circuit of relay 10' which in turn effects the deenergization of the 45 magnet M'-4 so that the switch 4S' is moved to its first position. In positions 1-6 inclusive of switch 4S' the first to sixth off-normal contacts of bank 4S'-6 are connected to the positive terminal of battery BAT' through conductor 323, contacts 324 of relay 34', conductor 325, wiper and eighth off-normal contact of bank 1S'-3 to the positive terminal of battery BAT' and in positions 7-21 inclusive the seventh to the twenty-first contacts of bank 4S'-6 are connected directly to the positive terminal of battery BAT'. Therefore, as soon as the switch 3S' sets up the check code, the code sender 4S' moves from its normal position to its twenty-second position.

Since only two line conductors are used, it is necessary that they be transferred from the code-receiving equipment to the code sending equipment in the remote station before the check code is transmitted to the dispatcher's office. 70 This result is accomplished by relay 35' which is energized through the wiper and contacts of bank 4S'-2 in positions 4-21 —inclusive of switch 4S'. By opening its contacts 304 and 305, relay 35' disconnects the code-receiving relay CRR' from 75

the line conductors L-1 and L-2, and by closing its contacts 326 and 327 transfers the line conductors to the contacts of the code-transmitting relay CTR' which is a three-position polarized relay and which is energized each time the wiper of bank 4S'-3 engages a contact connected either to the positive or negative terminal of battery BAT'. By closing its contacts 337, relay 35' completes a circuit from the positive terminal of battery BAT', contacts 333 of relay CSR', conductor 338, winding of relay 17', contacts 339 of relay 13', conductor 340, contacts 337 of relay 35', to the neutral terminal of battery BAT'. By closing its contacts 341, relay 17' completes a locking circuit for itself to the neutral terminal of battery BAT'.

When the wiper of bank 4S'-3 engages a contact which is connected to the negative terminal of battery BAT', the code-transmitting relay 20 CTR' closes its contacts 328 and 329 so that the line conductors L-1 and L-2 are respectively connected to the negative and positive terminals of battery BAT' and a negative impulse is transmitted over the line conductors. When the wiper 25 of bank 4S'-3 engages a contact which is connected to the positive terminal of battery BAT', the relay CTR' closes its contacts 330 and 331 so that the line conductors L-1 and L-2 are respectively connected to the positive and negative terminals of the battery BAT' and a positive impulse is transmitted over the line conductor.

In the dispatcher's office the impulses transmitted over the line conductors L-1 and L-2 by the operation of the code-transmitting relay 35 CTR' energizes the code-receiving relay CRR which is connected across the line conductors L-1 and L-2 by contacts 101 of relay 16^a, conductor 102, contacts 103 of relay 28, and wiper and eighteenth off-normal contact of bank 40 2S-3. When the code-transmitting relay CTR' is operated so that a negative impulse is transmitted over the line conductors, the code-receiving relay CRR closes its contacts 130 and when a positive impulse is transmitted over the line 45 conductors, the relay CRR closes its contacts 104. Therefore, when the code sender 4S' in the remote station reaches its fifth position and the code-transmitting relay CTR' is operated to transmit the starting impulse which is a negative impulse, the code-receiving relay CRR is operated to close its contacts 130 and thereby complete a circuit from the positive terminal of battery BAT through winding of relay 1, conductor 200, contacts 130 of relay CRR, conductor 131, 50 wiper and normal contact of bank 3S-2, winding of relay 10, contacts 203 of relay 9 to the negative terminal of battery BAT. By closing its contacts 204, relay 10 completes a locking circuit to the neutral terminal of battery BAT. As soon as switch 4S' leaves its fifth position, the starting impulse is cut off from the line conductors and relay CRR effects the deenergization of relay 7. By closing its contacts 205, relay 1 completes a 55 circuit from the negative terminal of battery BAT through contacts 205 of relay 1, conductor 206, contacts 207 of relay 10, conductor 208, wipers and normal contact of bank 3S-4, winding of operating magnet M-3 of switch 3S, interrupter contact IC-3 to the neutral terminal of battery BAT. Magnet M-3 then operates to effect the movement of switch 3S to its first position.

When switch 4S' reaches its seventh position and the code-transmitting relay CTR' is operated 75 to transmit the first impulse of the check code,

relay CRR closes its contacts 104 and completes a circuit from the positive terminal of battery BAT through the winding of relay 7, conductor 200, contacts 104 of relay CRR, conductor 105, wiper and first off-normal contact of bank 3S-1, conductor 209, winding of relay 13, conductor 210, contacts 211 of relay 9, to the negative terminal of battery BAT. By closing its contacts 212, relay 13 completes a locking circuit for itself to the neutral terminal of battery BAT. As soon as the switch 4S' leaves its position 7, the first impulse of the check code is cut off and relay CRR effects the deenergization of relay 7. A circuit is then completed from the negative terminal of battery BAT through contacts 205 of 15 relay 1, conductor 206, contacts 213 of relay 13, conductor 214, wiper and first off-normal contact of bank 3S-4, winding of magnet M-3, interrupter contact IC-3 to the neutral terminal of battery BAT. Magnet M-3 then operates to 20 effect the movement of switch 3S to its second position.

When switch 4S' reaches its ninth position and relay CTR' is operated to transmit the second impulse of the check code, which is a positive 25 impulse, relay CRR again closes its contacts 104 and completes a circuit from the positive terminal of battery BAT through winding of relay 7, conductor 200, contacts 104 of relay CRR, conductor 105, wiper and second off-normal contact 30 of bank 3S-1, conductor 215, winding of relay 15, conductor 216, contacts 211 of relay 9 to the negative terminal of battery BAT. By closing its contacts 216, relay 15 completes a locking circuit for itself to the neutral terminal of battery 35 BAT. As soon as switch 4S' leaves its position 9, the second impulse of check code is cut off and relay CRR effects the deenergization of relay 7. A circuit is then completed from the negative terminal of battery BAT through contacts 205 of 40 relay 1, conductor 206, contacts 217 of relay 15, conductor 218, wiper and second off-normal contact of bank 3S-4, winding of magnet M-3, interrupter contact IC-3 to the neutral terminal of battery BAT. Magnet M-3 then effects the 45 movement of switch 3S to its third position.

When switch 4S' reaches position 11, relay CTR' is operated to transmit the third impulse of the check code, which is a negative impulse. Relay CRR then closes its contacts 130 and a 50 circuit is completed from the positive terminal of battery BAT, through winding of relay 7, conductor 200, contacts 130 of relay CRR, conductor 131, wiper and third off-normal contact of bank 3S-2, conductor 219, winding of relay 18, conductor 220, contacts 203 of relay 9 to the negative terminal of battery BAT. By closing its contacts 221, relay 18 completes a locking circuit for itself to the neutral terminal of battery BAT. As soon as switch 4S' leaves its eleventh position, 60 the third impulse of the check code is cut off and relay CRR effects the deenergization of relay 7. A circuit is then completed from the negative terminal of battery BAT through contacts 205 of relay 1, conductor 206, contacts 222 of relay 18, 65 conductor 223, wiper and third off-normal contact of bank 3S-4, winding of magnet M-3, interrupter contact IC-3 to the neutral terminal of battery BAT. Magnet M-3 then effects the 70 movement of switch 3S to its fourth position.

When switch 4S' reaches its thirteenth position and relay CTR' transmits the fourth impulse of the check code, which is a positive impulse, relay CRR closes its contacts 104 and completes a circuit from the positive terminal of battery BAT 75

- through winding of relay 7, conductor 200, contacts 104 of relay CRR, conductor 105, wiper and fourth off-normal contact of bank 3S-1, conductor 224, winding of relay 19, conductor 210, contacts 211 of relay 9 to the negative terminal of battery BAT. By closing its contacts 225, the relay 19 completes a locking circuit for itself to the neutral terminal of battery BAT. As soon as switch 4S' leaves its thirteenth position, the fourth impulse of the check code is cut off and relay CRR effects the deenergization of relay 7. A circuit is then completed from the negative terminal of battery BAT through contacts 205 of relay 7, conductor 206, contacts 226 of relay 19, conductor 227, wiper and fourth off-normal contact of bank 3S-4, winding of magnet M-3, interrupter contact IC-3 to the neutral terminal of battery BAT. Magnet M-3 then effects the movement of switch 3S to its fifth position.
- When switch 4S' reaches its fifteenth position and relay CTR' transmits the fifth impulse of the check code, which is a negative impulse, relay CRR closes its contacts 130 and completes a circuit from the positive terminal of battery BAT through winding of relay 7, conductor 200, contacts 130 of relay CRR, conductor 131, wiper and fifth off-normal contact of bank 3S-2, conductor 228, winding of relay 22, conductor 229, contact 203 of relay 9 to the negative terminal of battery BAT. By closing its contacts 229, relay 22 completes a locking circuit for itself to the neutral terminal of battery BAT. As soon as switch 4S' leaves its fifteenth position, the fifth impulse of the check code is cut off and relay CRR effects the deenergization of relay 7. A circuit is then completed from the negative terminal of battery BAT through contacts 205 of relay 7, conductor 206, contacts 230 of relay 22, conductor 231, wiper and fifth off-normal contact of bank 3S-4, winding of magnet M-3, interrupter contact IC-3 to the neutral terminal of battery BAT. Magnet M-3 then effects the movement of the switch 3S to its sixth position.
- When switch 4S' reaches its seventeenth position and the relay CTR' transmits the sixth impulse of the check code, which is a negative impulse, relay CRR closes its contacts 130 and completes a circuit from the positive terminal of battery BAT through winding of relay 7, conductor 200, contacts 130 of relay CRR, conductor 131, wiper and sixth off-normal contact of bank 3S-2, conductor 232, winding of relay 24, conductor 220, contacts 203 of relay 9 to the negative terminal of battery BAT. By closing its contacts 233, relay 24 completes a locking circuit for itself to the neutral terminal of battery BAT. As soon as switch 4S' leaves its seventeenth position, the sixth impulse of the check code is cut off and relay CRR effects the deenergization of relay 7. A circuit is then completed from the negative terminal of battery BAT through contacts 205 of relay 7, conductor 206, contacts 234 of relay 24, conductor 235, wiper and sixth off-normal contact of bank 3S-4, winding of magnet M-3, interrupter contact IC-3 to the neutral terminal of battery BAT. Magnet M-3 then effects the movement of switch 3S to its seventh position.
- When switch 4S' reaches its nineteenth position and relay CTR' transmits the last impulse of the check code, which is a positive impulse, relay CRR closes its contacts 104 and completes a circuit from the positive terminal of battery BAT through winding of relay 7, conductor 200, contacts 104 of relay CRR, conductor 105, wiper and seventh off-normal contact of bank 3S-1, conductor 236, winding of relay 25, conductor 210, contacts 211 of relay 9 to the negative terminal of battery BAT. By closing its contacts 237, relay 25 completes a locking circuit for itself to the neutral terminal of battery BAT. By closing its contacts 238 relay 25 completes an energizing circuit for the winding of relay 14. As soon as switch 4S' leaves its nineteenth position, the last impulse of the check code is cut off and relay CRR effects the deenergization of relay 7. A circuit is then completed from the negative terminal of battery BAT through contacts 205 of relay 7, conductor 206, contacts 239 of relay 25, conductor 240, wiper and seventh off-normal contact of bank 3S-4 winding of magnet M-3, interrupter contact IC-3 to the neutral terminal of battery BAT. Magnet M-3 then effects the movement of switch 3S to its eighth position.
- When switch 4S' reaches position 21 and the code transmitting relay CTR' operates to transmit a positive impulse corresponding to the open position of the apparatus unit AU'-23, relay 25 CRR closes its contacts 104 and completes a circuit from the positive terminal of battery BAT through winding of relay 7, conductor 200, contacts 104 of relay CRR, conductor 105, wiper and eighth off-normal contact of bank 3S-1, winding of relay 11 to the negative terminal of battery BAT. By closing its contacts 242, relay 11 completes a circuit between the positive and neutral terminals of battery BAT for the master indication relay MIR so that it closes its contacts 243. The master indication relay is a two-position polarized relay and is so designed that it remains in the position to which it is last moved whenever the winding thereof is deenergized.
- Since the adjacent off-normal contacts 21 and 22 of bank 4S'-3 are connected together, and relay CTR' is made slightly slow-to-release by having the resistor R connected in shunt to its winding, relay CTR' maintains its armature in its operated position while the switch 4S' is moving from its twenty-first position to its twenty-second position. When the switch 4S' reaches its twenty-second position an energizing circuit for relay 12' is completed by the wiper and twenty-second off-normal contact of bank 4S'-4. After the switch 4S' has remained in its position 22 for a certain length of time, relay 35 whose circuit is interrupted by the wiper of bank 4S'-2 leaving its twenty-first off-normal contact opens its contacts 326 and 327 and thereby cuts off the indication impulse. Relay CRR then opens its contacts 104 and effects the deenergization of relay 7. A circuit is then completed from the negative terminal of battery BAT through contacts 205 of relay 7, conductor 206, contacts 260 of relay 11, conductor 261, wiper and eighth off-normal contact of bank 3S-4, winding of magnet M-3, interrupter contact IC-3 to the neutral terminal of battery BAT. Magnet M-3 then operates to effect the movement of switch 3S to its ninth position.
- A predetermined time after the indication impulse is cut off by the deenergization of relay 35, relay 8, which is of the slow-to-drop-out type, closes its contacts 243a. This relay 8, the circuit of which is opened at contacts 202 of relay 7, is so designed that the time interval between the different impulses transmitted by the code sender 4S' is not sufficiently long to allow 75

the relay to close its contacts 243^a. After the indication impulse is transmitted, however, the time interval is sufficient to allow this relay to operate. When the contacts 243^a close a circuit is completed from the negative terminal of battery BAT, through contacts 205 of relay 7, conductor 206, contacts 243^a of relay 8, wiper and ninth off-normal contact of bank 3S-3, winding of relay 27 to the neutral terminal of battery BAT. By closing its contacts 244, relay 27 completes a locking circuit for itself to the negative terminal of the battery which is independent of the contacts of the relays 7 and 8. By closing its contacts 245, relay 27 completes a circuit from the positive terminal of battery BAT through contacts 243 of relay MIR, contacts 245 of relay 27, conductor 246, contacts 247 of relay 13, contacts 248 of relay 15, conductor 249, contacts 250 of relay 18, conductor 251, contacts 252 of relay 19, conductor 253, contacts 254 of relay 22, conductor 255, contacts 256 of relay 24, conductor 257, contacts 258 of relay 14, conductor 259, winding of indication relay IR-23 to the neutral terminal of battery BAT. A circuit is also completed from conductor 259 through amber lamp AM-23, wiper and twenty-third off-normal contact of bank 1S-1, conductor 134, wiper and eighteenth off-normal contact of bank 2S-5, winding of relay 14^a to the neutral terminal of battery BAT. The direction of current flow in the winding of relay IR-23 is such as to cause the relay to close its contacts 155 and open its contacts 156 so that the green light G-23 is lighted and the red light R-23 is extinguished. The lighting of the amber lamp AM-23 indicates to the dispatcher that the selection has been properly made and that the selection check relay 14^a is energized so that it is now possible for him to operate the selected apparatus unit. It will be observed that the amber lamp AM-23 corresponding to the operated select key SK-23 can be lighted only when the circuit established through the selection relays 18-26 inclusive agrees with the contact on which the wipers of the code finding selector 1S at the dispatcher's office have stopped.

After the amber light AM-23 is lighted, the dispatcher moves the check key CK-23 to its opposite position thereby completing a circuit for the white light W-23. Then he operates the operate key OK so as to close its contacts 135 and 136. The closing of the contacts 135 completes a circuit from the negative terminal of battery BAT through the wiper and eighteenth off-normal contact of bank 2S-4, conductor 139, contacts 138 of relay 14^a, winding of relay 16^a, conductor 137, contacts 135 of key OK to the neutral terminal of battery BAT. Relay 16^a by closing its contacts 140 and 145 completes a circuit from the negative terminal of battery BAT through winding of relay 32, contacts 140 of relay 16^a, conductor 141, contacts 142 of relay 32, line conductor L-2, contacts 305 of relay 35^a, contacts 310 of relay 1', conductor 309, winding of high resistance relay 13', contacts 344 of relay 12', conductor 401, contacts 304 of relay 35^a, line conductor L-1, contacts 143 of relay 33, conductor 144, contacts 145 of relay 16^a to the positive terminal of battery BAT. Since the winding of relay 13' has a high resistance, the current in this circuit is not sufficient to cause relay 32 to pick up. Relay 13', however, closes its contacts 345 and connects the winding of relay 14' and contacts 346 in a series circuit around the winding of relay 13'. Relay 14' is

of the time delay pick-up type and is provided in the circuit so as to prevent any transient disturbance on the line from effecting the operation of a selected apparatus unit.

By closing its contacts 347, the relay 14' connects the winding of the code receiving relay CRR' across the line conductors L-1 and L-2. This circuit of the relay CRR' is from line conductor L-1 through contacts 304 of relay 35^a, conductor 401, winding of relay CRR', conductor 303, contacts 347 of relay 14', contacts 346 of relay 17', conductor 309, contacts 310 of relay 1', contacts 305 of relay 35' to line conductor L-2. The direction of current flow through the winding of relay CRR' causes this relay to close the contacts 406 and complete a circuit from the positive terminal of battery BAT' through the winding of relay 3', contacts 406 of relay CRR', wiper and eighth off-normal contact of bank 1S', conductor 456, contacts 352 of relay 34', conductor 353, contacts 334 of relay CSR', contacts 254 of relay 16', winding of relay 15', conductor 355, contacts 356 of relay 12' to the negative terminal of battery BAT'. By closing its contacts 351, relay 15' completes a locking circuit for itself which is independent of the contacts 334 of relay CSR'. By closing its contacts 358, relay 15' completes a circuit from the negative terminal of battery BAT' through contacts 358 of relay 15', conductor 359, contacts 360 of relay 14', conductor 361, wiper and twenty-third off-normal contact of bank 2S'-5, winding of control relay CR'-23 to the neutral terminal of battery BAT'. The current in this circuit causes relay CR'-23 to close its contacts 362 and thereby complete through the auxiliary contacts 363 an energizing circuit for the closing coil CC'-23 of apparatus unit AU-23.

When both of the relays 14' and CRR' are connected in parallel with the high resistance relay 13' in the remote station, the current through the relay 32 in the dispatcher's office is sufficient to cause this relay to pick up. By closing its contacts 146, the relay 32 completes a circuit for the operate lamp OL so that this lamp is lighted as long as the control impulse is being transmitted to the control relay of the selected apparatus unit. By closing its contacts 157 and 158, the relay 32 completes shunt circuits around the contacts 142 and 143 of relay 33 so that the subsequent energization of relay 33 does not cut off the control impulse. By closing its contacts 147, relay 32 completes a circuit from the positive terminal of battery BAT through contacts 136 of key OK, conductor 148, winding of relay 33, conductor 149, contacts 147 to the neutral terminal of battery BAT. By closing its contacts 150, relay 33 completes a locking circuit for itself around the contacts 147 of relay 32. Therefore, the relay 33 remains energized as long as the operate key is maintained in its "operate" position so that when the relay 32 subsequently drops out, another control impulse cannot be transmitted until after the key OK has first been returned to its normal position to effect the deenergization of relay 33.

When the apparatus unit AU-23 closes, it effects the opening of its auxiliary contacts 321 and the closing of its auxiliary contacts 322 so that the current through the windings of relays CSR' and CTR' reverses. This reversal of current causes the relay CSR' to open its contacts 333 and 334 and close its contacts 335 and 336 and the relay CTR' to open its contacts 330 and 331 and close its contacts 328 and 329. The opening

of the contacts 333 of relay CSR' interrupts the circuit of relay 17' so that it opens its contacts 341 and 346. By opening its contacts 346, relay 17' effects the disconnection of the relays 14' and 5 CRR' from across the line conductors so that the control current is decreased below the drop out value of the relay 32 in the dispatcher's office. Relay 32 then drops out and by opening its contacts 157 and 158 cuts off the control impulse 10 and by closing its contacts 153 transfers the line conductors L-1 and L-2 to the receiving circuit at the dispatcher's office.

The operation of the apparatus unit AU'-23 also interrupts the locking circuit of indicating 15 relay IA'-23, but as soon as the apparatus unit reaches its new position an energizing circuit for the relay IA'-23 is completed through the wiper and twenty-third contact of bank 2S'-3, conductor 387 and contacts 390 of relay 34'.

20 When the control impulse is cut off, relay 13' at the remote station drops out and completes a circuit from the negative terminal of battery BAT' through the winding of relay 35', conductor 369, contacts 368 of relay 17', conductor 367, contacts 366 of relay 13', conductor 365, wiper and twenty-second off-normal contact of bank 4S'-2 to the neutral terminal of battery BAT'. Relay 35' by closing its contacts 326 and 327, transmits a negative impulse over the line conductors L-1 25 and L-2 since the contacts 328 and 329 of the code transmitting relay CTR' are now closed. By closing its contacts 331, relay 35' also completes a circuit from the negative terminal of battery BAT' through contacts 335 of relay CSR', conductor 338, winding of relay 17', contacts 339 of relay 13', conductor 340, contacts 331 of relay 35' to the neutral terminal of battery BAT'. Relay 30 35' by closing its contacts 341 completes a locking circuit for itself which is independent of the contacts 337 of relay 35'. By opening its contacts 368, relay 17' interrupts the above-traced circuit for the relay 35' so that the indication impulse is cut off and the line conductors L-1 and L-2 are 40 reconnected to the control impulse receiving apparatus at the remote station. Since the relay 17' is of the slow-to-pick-up type, the indication impulse is transmitted over the line conductors for a predetermined time.

At the dispatcher's office, the indication impulse causes the code receiving relay CRR to 45 close its contacts 130 so that a circuit is completed from the positive terminal of battery BAT through the winding of relay 7, conductor 200, contacts 130 of relay CRR, conductor 131, wiper and ninth off-normal contact of bank 3S-2, conductor 265, contacts 266 of relay 27, conductor 267, winding of relay 12 to the negative terminal of battery BAT. By closing its contacts 268, relay 12 reverses the current through the winding of relay MIR so that it opens its contacts 243 50 and closes its contacts 269. This results in a reversal of current through the indicating relay IR-23 so that it opens its contacts 155 and closes its contacts 156 thereby extinguishing the green light G-23 and the white light W-23 and lighting the red light R-23.

The apparatus unit AU'-23 may be opened again, if desired, by moving the control key CK-23 to the opposite position and again moving 55 the operate key to its "operate" position. The operation of the apparatus in the remote station is the same as for the closing operation except that the control selection relay CSR' now has its contacts 336 closed so that the control impulse 60 causes the relay 16' to be energized instead of the

relay 15'. In this case relay 16' by closing its contacts 371 applies positive potential to the control relay CR'-23 so that it closes its contacts 372 and completes through the auxiliary contacts 373 an energizing circuit for the trip coil TC'-23 5 of the apparatus unit AU'-23. The opening of the apparatus unit AU'-23 reverses the current through the code transmitting relay CTR' so that the indication impulse is a positive impulse. In the dispatcher's office this indication impulse is 10 received as before except that relay 11 is energized by the positive impulse to effect the operation of the indicating relay IR-23 so as to extinguish the red lamp R-23 and to light the green lamp G-23. 15

The apparatus unit AU'-23 may be operated as many times as desired before the selection is released. To prevent the selected apparatus unit from pumping while the operate key OK is pressed, the relay 15' or 16' when energized, 20 completes a locking circuit for itself around the contacts of the relay CSR' and opens the circuit of the other relay. Thus the first of those two relays to be energized remains energized until the control impulse is released. 25

After the last operation has been performed by the dispatcher he can release the selection by moving the select key SK-23 to its normal position. The closing of the contacts 109 of the select key SK-23 connects the twenty-third off-normal 30 contact of the bank 1S-6 to the positive terminal of battery BAT so that a notching circuit is completed for the magnet M-1 to move the switch 1S to position 24. A notching circuit is then completed directly to the positive terminal of the battery BAT to restore the switch 1S to its normal 35 position.

When switch 1S moves from its position 23, relay 4 drops out and by closing its contacts 115 completes a notching circuit for the magnet M-2 40 through the wiper and eighteenth off-normal contact of bank 2S-6. Magnet M-2 then effects the movement of the switch 2S to position 19. Since the nineteenth to the twenty-fourth off normal contacts of bank 2S-6 are connected 45 directly to the negative terminal of the battery BAT, a notching circuit is then completed for the magnet M-2 to restore the switch 2S to its normal position.

As soon as switch 1S leaves its twenty-third 50 position, the heretofore traced circuit for the relay 14^a is opened by the wiper of bank 1S-1 leaving its twenty-third off-normal contact. By closing its contacts 160 relay 14^a completes a circuit from the negative terminal of battery 55 BAT through contacts 271 of relay 27, conductor 272, contacts 160 of relay 14^a, conductor 161, winding of relay 28 to the neutral terminal of the battery BAT. By closing its contacts 164, relay 28 completes a circuit from the positive 60 terminal of battery BAT through winding of relay 1, conductor 200, contacts 164 of relay 28, conductor 165, winding of relay 9 to the negative terminal of battery BAT. By opening its contacts 203 and 211, relay 9 opens all of the locking 65 circuits of the energized selection relays in the dispatcher's office. By closing its contacts 162, relay 28 completes a circuit from the negative terminal of battery BAT through contacts 162 of relay 28, conductor 273, wiper and ninth off-70 normal contact of bank 3S-4, winding of magnet M-3, interrupter contact IC-3 to the neutral terminal of battery BAT. The magnet M-3 then effects the movement of switch 3S to its tenth position. When the switch 3S leaves posi- 75

tion 9 the heretofore traced locking circuit of relay 27 is interrupted so that it drops out and effects the deenergization of the relay 28 which, in turn, by opening its contacts 164 effects the deenergization of the relay 7. After the relay 7 has remained deenergized for a sufficient length of time to allow relay 8 to close its contacts 243^a, a notching circuit is completed from the negative terminal of battery BAT through contacts 205 of relay 7, contacts 243^a of relay 8, wiper and off-normal contacts 10-24 inclusive of bank 3S-3, winding of magnet M-3, interrupter contact IC-3 to the neutral terminal of battery BAT. Magnet M-3 then notches the switch 3S 15 to its normal position.

While the relay 28 is energized, the contacts 166 thereof complete a circuit for the code transmitting relay CTR so that a negative impulse is transmitted over the line conductors L-1 and 20 L-2. In the remote station this negative impulse causes the code receiving relay CRR' to close its contacts 402 and complete a circuit from the positive terminal of battery BAT' through the winding of relay 3', contacts 402 of relay 25 CRR', wiper and eighth off-normal contact of bank 1S'-2, conductor 465, winding of relay 36' to the negative terminal of battery BAT'. By opening its contacts 409 and 420, relay 36' interrupts the locking circuits of the energized 30 selection relays in the remote station so that they are restored to their normal positions. By closing its contacts 466, relay 36' completes a circuit from the negative terminal of battery BAT' through contacts 466 of relay 36', conductor 467, 35 wiper and eighth off-normal contact of bank 1S'-6, winding of magnet M'-1, interrupter contact IC'-1, to the neutral terminal of battery BAT'. Magnet M'-1 then effects the movement of switch 1S' to its ninth position. In positions 9-24 inclusive of switch 1S' a notching circuit is completed for the magnet M'-1 through the wiper and contacts of bank 1S'-5, contacts 452 of relay 4' and contacts 404 of relay 3' after the release impulse is cut off from the line conductors so that the switch 1S' is restored to its 45 normal position.

When switch 1S' leaves its eighth position, the circuit of relay 6' is interrupted by the wiper 1S'-4 leaving its eighth off-normal contact. 50 By opening its contacts 440, relay 6' interrupts the heretofore traced notching circuit for magnet 2S' so that the switch 2S' remains in its twenty-third position until another apparatus unit has been selected or an automatic operation of an 55 apparatus unit occurs. Since the position of switch 3S' is determined by the position of switch 2S', switch 3S' also remains in its twenty-third position.

When the selection relays 20'-33' inclusive in 60 the remote station are deenergized, the heretofore traced circuit of relay 34' is interrupted so that this relay drops out. By closing its contacts 375, relay 34' completes a circuit from the positive terminal of battery BAT' through contacts 375, conductor 376, wiper and twenty-second to twenty-fourth off-normal contacts of bank 4S'-6, interrupter contacts IC'-4, winding of relay 10' to the neutral terminal of battery BAT'. By closing its contacts 320, relay 10' 65 completes a circuit through the wiper and contacts of bank 4S'-5 for the slow-to-pick up relay 11'. Relay 11', in turn, completes a circuit for the magnet M'-4 through contacts 377. Magnet M'-4 therefore operates to restore the switch 70 75 4S' to its normal position. Relay 11' is con-

nected in the notching circuit of magnet M'-4 to provide slower stepping of the switch 4S' from the position 22 to its normal position. When the selector switches 1S' and 4S' reach their normal 5 positions, the heretofore traced check circuit is completed to effect the energization of the relay 1 which by closing its contacts 100 completes a circuit for the start lamp STL.

When the supervisory equipment is at rest and an apparatus unit changes its position, an indication is immediately transmitted to the dispatcher's office. As an example, it will be assumed that the apparatus unit AU'-23 is closed and opened automatically. While the apparatus unit AU'-23 is closed the indication auxiliary 10 relay IA'-23 is maintained energized by a locking circuit which is completed from the negative terminal of battery BAT' through auxiliary contacts 322 on apparatus unit AU'-23, winding of relay IA'-23, contacts 380 of relay 20 IA'-23 to the neutral terminal of battery BAT'.

When the apparatus unit AU'-23 opens, the locking circuit of relay IA'-23 is opened so that relay IA'-23 drops out and closes its contacts 381. A notching circuit is then completed for 25 the magnet M'-2 to move the switch 2S' from whatever position it may be in to position 23 which is the position allotted to the apparatus unit AU'-23. This notching circuit is from the positive terminal of battery BAT', through wiper 30 and normal contact of bank 1S'-3, conductor 323, contacts 381 of relay IA'-23, conductor 441, contacts 311 of relay 19', contacts 312 of relay 1', winding of magnet M'-2, interrupter contact IC'-2 to the neutral terminal of battery BAT'. 35 When switch 2S' reaches position 23, relay 7' is energized to open its contacts 312 and interrupt the above-traced notching circuit for the magnet M'-2. The circuit of relay 7' is from the negative terminal of battery BAT' through winding of 40 relay 7', wiper and twenty-third off-normal contact of bank 2S'-2, conductor 454, contacts 382 of relay IA'-23, winding of relay 9', conductor 400, wiper and normal contact of bank 1S'-4 to the positive terminal of battery BAT'. While 45 the switch 2S' is moving to its twenty-third position, switch 3S' is operated in a manner heretofore described to move to its twenty-third position. As soon as relay 7' is energized and switch 3S' stops in position 23 so that relay 8' is maintained in its energized position, a circuit is completed from the negative terminal of battery BAT' through contacts 315 of relay 8', contacts 316 of relay 1', conductor 317, contacts 471 of relay 36', conductor 319, wiper and normal contact of bank 4S'-6, interrupter contact IC'-4, 50 winding of relay 10' to the neutral terminal of battery BAT'. Relay 10' then operates to establish a notching circuit for magnet M'-4 so that the code sender 4S' operates to transmit the 55 code of apparatus unit AU'-23 in the manner above described to the dispatcher's office.

As soon as switch 4S' leaves its normal position, the heretofore described circuit for the zero position check relay 1 is opened. By opening its contacts 100, relay 1 extinguishes the start lamp STL, and by opening its contacts 107, relay 1 65 interrupts the locking circuit of relay 2. By closing its contacts 127, relay 2 completes, through contacts 117 of start key ST, a circuit for the 70 alarm ALM. Therefore the dispatcher is informed by the alarm and the extinguishing of the lamp STL that an automatic operation of an apparatus unit has occurred.

In the dispatcher's office the code is received by 75

code receiving relay CRR which in the normal position of switch 2S is connected across the line conductors by the wiper and normal contact of bank 2S-3. This code effects the energization of the selection relays 13, 15, 18, 19, 22, 24, 25, and 14 in the same manner as described for the check code and the relay 11 is energized to effect the operation of the relay MIR so that its contacts 243 are closed. Therefore, when the relay 27 is energized in response to the switch 3S reaching its ninth position, indicating relay IR-23 is energized so as to close its contacts 155 and open its contacts 156 to effect the lighting of the green lamp G-23 and the white lamp W-23 and the extinguishing of the red lamp R-23.

Since the switch 2S is in its normal position, the relay 14a is deenergized and therefore the energization of relay 27 also completes a circuit for relay 28 from the negative terminal of battery BAT through contacts 271 of relay 27, conductor 272, contacts 160 of relay 14a, conductor 161, winding of relay 28, to the neutral terminal of battery BAT. The energization of relay 28 opens the locking circuits of the energized selection relays in the dispatcher's office by effecting the energization of relay 9 and effects the movement of switch 3S to its normal position and operates code transmitting relay CTR so that a release impulse is transmitted over the line conductors 30 L-1 and L-2 in the manner previously described.

In the remote station the switch 4S' does not stop in position 22 but continues to operate until it reaches its normal position since a notching circuit for magnet M'-4 is completed through the contacts 375 of the deenergized relay 34' when the switch 4S' is in positions 22-24 inclusive. In positions 23 and 24 of switch 4S' a circuit for relay 18 is completed through the wiper and contacts of bank 4S'-4. By closing its contacts 385, relay 18' connects the winding of relay 19' across the line conductor L-1 and L-2 so that the relay 19' receives the release impulse sent out from the dispatcher's office. The notching of switch 4S' in positions 21-24 inclusive is slowed down by the addition of relay 11' so as to insure that the relay 19' remains connected across the line conductors for a sufficient length of time to receive this release impulse. By closing its contacts 386, relay 19' completes a circuit from the positive terminal of battery BAT' through auxiliary contacts 321 on apparatus unit AU'-23, winding of relay IA'-23, wiper and twenty-third off-normal contact of bank 2S'-3, conductor 387, contacts 386, of relay 19', to the neutral terminal of battery BAT'. By closing its contacts 388 relay IA'-23 completes a locking circuit for itself around the contacts 386 of relay 19' so that relay IA'-23 remains energized until the apparatus unit AU'-23 again changes its position.

When switch 4S' reaches its normal position, relay 1' is energized and completes the above-traced zero position check circuit so that the relay 1 in the dispatcher's office is energized to effect the lighting of the start lamp STL.

Thus, the indication of the changed condition of the apparatus unit AU'-23 is sent to the dispatcher's office and the supervisory equipment is then reset for the next operation. The dispatcher extinguishes the white lamp W-23 by turning the control key CK-23 to the position thereof which agrees with that of the open circuit breaker. He cuts off the alarm by operating his alarm key AK which completes a circuit

for the alarm relay 2 either through the contacts 107 or 171 depending upon the position of the check relay 1. Relay 2 by closing its contacts 108 completes a locking circuit for itself so that the dispatcher may immediately release the alarm key.

While I have, in accordance with the patent statutes, shown and described my invention as applied to a particular system and as embodying various devices diagrammatically indicated, changes and modifications will be obvious to those skilled in the art and I therefore aim in the appended claims to cover all such changes and modifications as fall within the true spirit and scope of my invention.

What I claim as new and desire to secure by Letters Patent of the United States is:

1. In a supervisory control system, a first station, a second station, apparatus units at said second station, two line conductors interconnecting said stations, means including said conductors in series for selecting any of said units for operation, a control device at said first station for controlling the operation of a selected apparatus unit, means responsive to the movement of said device to a predetermined position for causing a limited current to flow through said conductors in series, means controlled by said limited current for effecting an increase in the current through said conductors in series and the operation of the selected apparatus unit, means responsive to the operation of the selected apparatus unit for decreasing the current through said conductors, and means responsive to said increase and subsequent decrease in the current through said conductors for preventing said control device from again effecting the flow of current through said conductors while said control device remains in said predetermined position.

2. In a supervisory control system, a first station, a second station, apparatus units at said second station, two line conductors interconnecting said stations, means including said conductors in series for selecting any of said units for operation, a control device at said first station for controlling the operation of a selected apparatus unit, means responsive to the movement of said device to a predetermined position for causing a limited current to flow through said conductors in series, timing means, means responsive to said limited current for effecting the operation of said timing means, means controlled by said timing means for effecting after a predetermined time interval an increase in the current through said conductors and the operation of a selected apparatus unit, means responsive to the operation of the selected apparatus unit for decreasing the current through said conductors, and means responsive to said increase and subsequent decrease in the current through said conductors for preventing said control device from again causing current to flow through said conductors while said control device remains in said predetermined position.

3. In a supervisory control system, a first station, a second station, apparatus units at said second station, two line conductors interconnecting said stations, means including said conductors in series for selecting any of said units for operation, a control device at said first station for controlling the operation of a selected apparatus unit, a relay, means responsive to the movement of said device to a predetermined po-

- sition for connecting said source in series with said conductors and said relay, a time relay, means responsive to the energization of said first-mentioned relay for completing an operating circuit for said time relay through said conductors in series, a control relay, means responsive to the operation of said time relay for completing an operating circuit for said control relay through said conductors in series, means responsive to the operation of said control relay for effecting the operation of the selected apparatus unit, means responsive to the operation of the selected apparatus unit for interrupting the circuits of said time and control relays for a predetermined time interval, and means responsive to the current variations through said conductors produced by the completion and subsequent interruption of the circuits of said time and control relays for effecting the disconnection of said source from said conductors and for maintaining them disconnected as long as said control device remains in said predetermined position.

4. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series of a predetermined number of impulses of different character permuted individual to the operated control device, selective means at said controlled station responsive to said impulses for selecting one of said units, means responsive to the selection of a unit for effecting the transmission through said conductors in series of a predetermined number of impulses of different character permuted individual to the selected unit, selective means at said controlling station responsive to said last mentioned impulses for selecting the signalling devices individual to the selected unit, means including said conductors in series for operating the selected unit, means including said conductors in series for controlling the signalling device individual to the selected unit in accordance with the position thereof, and switching means at each station for controlling the connections to said line conductors so as to effect said selecting, operating, and controlling operations.

5. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series of a predetermined number of impulses of opposite polarity permuted individual to the operated control device, selective means at said controlled station responsive to said impulses for selecting one of said units, means responsive to the selection of a unit for effecting the transmission through said conductors in series of a definite number of impulses of opposite polarity permuted individual to the selected unit, selective means at said controlling station responsive to said last mentioned impulses for selecting the

signalling devices individual to the selected unit, means including said conductors in series for operating the selected unit, means including said conductors in series for controlling the signalling devices individual to the selected unit in accordance with the position thereof, and switching means at each station for controlling the connections to said line conductors so as to effect said selecting, operating, and controlling operations.

6. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series of a predetermined number of impulses of different character permuted individual to the operated control device, selective means at said controlled station responsive to said impulses for selecting one of said units, means responsive to the selection of a unit for effecting the transmission through said conductors in series of a predetermined number of impulses of different character permuted individual to the selected unit followed by an indicating impulse of a character dependent upon the position of the selected unit, selective means at said controlling station responsive to said last mentioned predetermined number of impulses for selecting the signalling devices individual to the selected unit, means responsive to said indicating impulse for controlling the operation of the selected signalling device, means including said conductors in series for operating the selected unit, and switching means at each station for controlling the connections to said line conductors so as to effect said selecting, operating, and controlling operations.

7. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series of a predetermined number of impulses of different character permuted individual to the operated control device, selective means at said controlled station responsive to said impulses for selecting one of said units, means responsive to the selection of a unit for effecting the transmission through said conductors in series of a predetermined number of impulses of different character permuted individual to the selected unit followed by an indicating impulse of a character dependent upon the position of the selected unit, selective means at said controlling station responsive to said last mentioned predetermined number of impulses for selecting the signalling device individual to the selected unit, means responsive to said indicating impulse for controlling the operation of the selected signalling devices, means including said conductors in series for operating the selected unit from the controlling station only if the selected unit corresponds to the operated control device, and switching 75

means at each station for controlling the connections to said line conductors so as to effect said selecting, operating, and controlling operations.

5 8. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series 15 of a predetermined number of impulses of different character permuted individual to the operated control device, selective means at said controlled station responsive to said impulses for selecting one of said units, means responsive to 20 the selection of a unit for effecting the transmission through said conductors in series of a predetermined number of impulses of different character permuted individual to the selected unit followed by an indicating impulse of a polarity 25 dependent upon the position of the selected unit, selective means at said controlling station responsive to said last mentioned predetermined number of impulses for selecting the signalling devices individual to the selected unit, means responsive to 30 said indicating impulse for controlling the operation of the selected signalling devices, means operative only if the selected unit corresponds to the operated control device for transmitting through said conductors in series 35 an operating impulse of a predetermined polarity, means at the controlled station responsive to said operating impulse for operating the selected unit, and switching means at each station for controlling the connections to said line conductors so as to effect said selecting, operating, and controlling operations.

9. In a supervisory control system, a controlling station, a controlled station, a plurality of apparatus units at said controlled station, two line conductors interconnecting said stations, control devices at said controlling station individual to said units, means responsive to a predetermined operation of any of said control devices for effecting the transmission through said conductors in series of a predetermined number of impulses of different character permuted individual to the operated control device, selective means at said controlled station responsive to said impulses for selecting one of said units, means responsive to the selection of a unit for effecting the transmission through said conductors in series of a predetermined number of impulses of different character permuted individual to the selected unit followed by an indicating impulse of a character dependent upon the position of the selected unit, selective means at said controlling station responsive to said last mentioned predetermined number of impulses for selecting the signalling devices individual to the selected unit, means responsive to said indicating impulse for controlling the operation of the selected signalling devices, means operative only if the selected unit corresponds to the operated control device for transmitting through said conductors in series an operating impulse of a predetermined character, means at the controlled station responsive to said operating impulse for operating the selected unit, means responsive to said operation of the selected unit for transmitting through said conductors in series an indicating impulse 75

to effect the operation of the selected signalling devices in accordance with the new position of the selected unit, and switching means at each station for controlling the connections to said line conductors so as to effect said selecting, operating, and controlling operations.

10. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series of a predetermined number of impulses of opposite polarity permuted individual to the operated control device, selective means at said controlled station responsive to said impulses for selecting one of said units, means responsive to the selection of a unit for effecting the transmission through said conductors in series of a predetermined number of impulses of opposite polarity permuted individual to the selected unit followed by an indicating impulse of a polarity dependent upon the position of the selected unit, selective means at said controlling station responsive to said last mentioned predetermined number of impulses for selecting the signalling devices individual to the selected unit, means responsive to said indicating impulse for controlling the operation of the selected signalling devices, means operative only if the selected unit corresponds to the operated control device for transmitting through said conductors in series an operating impulse of a predetermined polarity, means at the controlled station responsive to said operating impulse for operating the selected unit, and switching means at each station for controlling the connections to said line conductors so as to effect said selecting, operating, and controlling operations.

11. In a supervisory control system, a controlling station, a controlled station, a plurality of apparatus units at said controlled station, two line conductors interconnecting said stations, control devices at said controlling station individual to said units, signalling devices at said controlling station individual to said units, means responsive to a predetermined operation of any of said control devices for effecting the transmission through said conductors in series of a predetermined number of impulses of opposite polarity permuted individual to the operated control device, selective means at said controlled station responsive to said impulses for selecting one of said units, means responsive to the selection of a unit for effecting the transmission through said conductors in series of a predetermined number of impulses of opposite polarity permuted individual to the selected unit followed by an indicating impulse of a polarity dependent upon the position of the selected unit, selective means at said controlling station responsive to said last mentioned predetermined number of impulses for selecting the signalling devices individual to the selected unit, means responsive to said indicating impulse for controlling the operation of the selected signalling devices, means operative only if the selected unit corresponds to the operated control device for transmitting through said conductors in series an operating impulse of a predetermined polarity, means at the controlled station responsive to said operating impulse for 75

operating the selected unit, means responsive to said operation of the selected unit for transmitting through said conductors in series an indicating impulse of a predetermined polarity to effect the operation of the selected signalling devices in accordance with the new position of the

selected unit, and switching means at each station for controlling the connections to said line conductors so as to effect said selecting, operating, and controlling operations.

JAMES H. OLIVER. 5
